UNITED STATES PATENT OFFICE.

GEORGE H. RICE, OF NEW YORK, N. Y.

DESIGN FOR A FRAME.

No. 38,394.

Specification for Design.

Patented Jan. 1, 1907.

Application filed November 16, 1906. Serial No. 343,771. Term of patent 3½ years.

To all whom it may concern:

Be it known that I, GEORGE H. RICE, a citizen of the United States, residing in the city of New York, borough of Brooklyn, in the county of Kings and State of New York, have invented a new, original, and ornamental Design for a Frame, of which the following is a specification, reference being had to the accompanying drawing, forming part thereof.

The figure is a plan view of a frame, showing my new design.

I claim—

The ornamental design of a frame, as shown.

GEORGE H. RICE.
